UNITED STATES PATENT OFFICE

ADOLPH M. AUGSTEIN, OF GREAT NECK, NEW YORK

DESIGN FOR A SWEATER

Application filed October 19, 1929. Serial No. 33,113. Term of patent 3½ years.

To all whom it may concern:

Be it known that I, ADOLPH M. AUGSTEIN, a citizen of the United States of America, and a resident of the town of Great Neck, Long Island, county of Nassau, State of New York, have invented a new, original, and ornamental Design for a Sweater, of which the following description, in connection with the accompanying drawing, is a specification.

The single figure of the drawing is a plan view of a sweater showing my new design. The characteristic feature of my new design resides in the border. The border ornamentation extends entirely around the sweater.

I claim as my invention:

The ornamental design for a sweater, substantially as shown and described.

ADOLPH M. AUGSTEIN.
